UNITED STATES PATENT OFFICE.

WILLIAM VINCENT FOLEY, OF NEW BRUNSWICK, NEW JERSEY.

REFLECTOR.

1,408,875.

Specification of Letters Patent.

Patented Mar. 7, 1922.

Application filed March 12, 1918. Serial No. 222,004.

To all whom it may concern:

Be it known that I, WILLIAM VINCENT FOLEY, a citizen of the United States, residing at New Brunswick, in the county of 5 Middlesex and State of New Jersey, have invented certain new and useful Improvements in Reflectors, of which the following is a specification.

This invention relates to reflectors for use 10 in apparatus for motion-picture projection and other purposes, and is especially useful in effecting the reflection of light rays from an incandescent electric lamp through a condensing lens on a moving-picture film or 15 other object or material to be either illuminated or subjected to the action of reflected light rays passed through a condensing lens.

While the present invention is an improvement 20 in reflectors, yet as they are of a special character of great and novel utility in special if not all uses, I set forth my present invention in an apparatus and in cooperating relations to other things in order to show forth clearly the merits of the present invention. Said apparatus is not herein claimed, 25 as it forms the subject-matter of my application Serial No. 217,083 of even date, filed Feb. 14, 1918, on which Patent No. 1,286,269 was granted December 3, 1918.

The objects of the invention are to conserve 30 and utilize a maximum quantity of light emanating from an incandescent electric lamp; and to produce a reflector of high efficiency and economy for use in motion-picture projecting machines; or for use in treatment of any material or object requiring exposure or subjection to light rays which travel from a source of light through any suitable condensing lens. As I do not know 35 all the industries in which my reflector may be practically useful, I take pains herein not to limit my invention merely to use in motion-picture projecting machines, which use however is one that I have given particular 40 attention to and one in which the invention is considered to be of very marked advantage.

In the accompanying drawings forming a 50 part hereof and illustrating the principle of this invention in the best mode now known to me of applying that principle,

Fig. 1 is a central lengthwise vertical section of the preferred form of apparatus in 55 which my new reflector is installed when it is used for motion-picture projections;

Fig. 2 is a front end, and

Fig. 3 a rear end elevation, and

Fig. 4 a side elevation of the preferred form of the zone-shaped reflector removed.

Assuming that there is used in apparatus 60 containing the present invention, a T-20 bulb, 600 watt, 20 ampere, 30 volt, Mazda C lamp such as is well known for projection service; also that such lamp has a maximum efficiency of about 1.2 candle power per watt, 65 or 720 candle power in all; also that a suitable condensing lens is used; and that in operation with the incandescent filament there is also used a suitable concave reflector 70 back of the lamp and an outwardly-flaring 75 faceted reflector that is approximately concentric with the point of light which is forwards of the concave reflector, the outwardly flaring reflector having its large end extending towards the condensing lens; and assuming also that the reflecting facets are 76 in effective number as herein shown in the preferred form of the outwardly-flaring reflector, and that each such facet reflects an image of the incandescent filament which is 80 also reflected in the concave mirror,—we have the following approximate results:

The point of light in operation with the concave reflector will yield about 80% of the candle power of the lamp, or 576 candle 85 power. And each facet reflection will yield about 10% of the candle power yielded by the point of light in operation with the concave mirror,—or 76 times 10% of 576, which equals 4377.6 candle power. The latter being 90 added to the candle power yielded by the point of light from the concave mirror, gives a total candle power reflected through the condensing lens of about 4953.

Such a theoretical total useful candle 95 power so obtained is comparable in ultimate effect with that often obtained by the use of an ordinary arc lamp; makes it possible to substitute incandescent for arc lights in motion-picture outfits in many installations and 100 with important advantages as regards safety, power economy, and cost of insurance; and results in a useful and desirable apparatus that not only has marked power of throwing its light to a greater working distance in motion-picture apparatus than has heretofore been possible with incandescent lamps, but also gives clearer illumination to the marginal portions of pictures projected on a screen than has been heretofore obtained. 110

My new reflector comprises in its preferred form an outwardly-flaring reflector which, described in mathematical terms with reference to its cross-sectional contour, is a 5 segment of a hollow sphere included between two parallel planes that are perpendicular to the axis; in other words it is a zone-shaped annulus. The smaller or bottom opening of the zone-shaped reflector 10 subtends about 64° of the surface of a sphere, and the width of the annulus from its smaller end to its outward end measures about 43° along the circumference of the sphere. Preferably the larger end of the 15 zone-shaped reflector is provided with a forwardly-extending conoidal rim the inner surface of which is at an angle of $25\frac{1}{2}^\circ$ to a tangential line parallel with the axis, the rearward spherical and the forward conoidal portions being preferably integral and together having a surface measurement corresponding to 180° along the surface of a 20 sphere.

Referring to the drawings, 1 is a supporting frame or casing shown in a form commonly known as a lamp house; 2 an incandescent electric lamp bulb having a threaded socket member 3 which screws into a vertical interiorly and exteriorly threaded 25 socket member 4 that is lengthwise adjustable in a collar 5 fixed to the upper wall of the lamp house concentrically with a hole through the wall. The lamp filament is indicated by 7. Forwardly of the lamp at a 30 proper distance understood by all skilled in the art, the lamp house is provided with a forwardly-extending lens tube 8 wherein is placed a duplex condensing lens comprising in the preferred form of the invention a pair 35 of plano-convex lenses 9, 9 spaced apart with their convex sides opposed. The long axis of the lamp is at right angles to the principal focal axis of the duplex condensing lens, or what is the same thing, to the axis 40 of the lens tube. The inner side of the bottom wall of the lamp house is provided with a lengthwise-extending dovetailed groove forming a guideway 10 parallel and opposed to a prolongation of the axis of the lens 45 tube. The upstanding support 11 of a forwardly and outwardly flaring tubular reflector which in its preferred form is the annular spherical zone-shaped reflector 12 hereinafter more particularly described, has a dovetail foot 13 which fits slidably in the dovetail guideway. The support 11 has a 50 hole through which the front end portion of an adjusting rod 14 is loosely mounted and held in place by a head 15 at the front 55 and a collar 16 at the rear side of the support. The adjusting rod is rearwardly threaded at 17 and passes through a threaded boss 18 in the rear end wall of the lamp house exteriorly of which it has a knurled head 19. Back of the annular, spherical 60

zone-shaped reflector there is a concave reflector 20 shown as an imperforate parabolic reflector, to the center of which the axis of the condenser lens tube is perpendicular. This parabolic reflector is held in a cross-sectionally round support 21 to the back side of which a rearwardly-extending adjusting rod 22 is fixed, the rod being rearwardly threaded at 23 and passing through an interiorly-threaded boss 24 fixed in the rear wall of the lamp house exteriorly of which it has a knurled head 25. When parabolic reflectors having perforations through which lamp sockets are inserted are used, a loss of 70 reflected rays occurs. 75

The diameter of the parabolic mirror support 21 is slightly less than the interior diameter of the rear end opening 26 of the annular spherical zone-shaped reflector; and the parabolic mirror may be moved in and out through such opening 26 for the relative adjustment of the reflecting surfaces of the parabolic and zone-shaped reflectors. Relatively to the filament 7 or point of light, the zone-shaped reflector is adjustable by the 80 screw 14 and the parabolic mirror is adjustable by the screw 23, the filament being adjustable to the principal focal axis of the condenser lenses by the threaded socket member 6 in the fixed collar 5. 85

The lamp house is desirably ventilated by means of an air-pipe 27 the discharge end of which is adjacent the metal lamp-socket members within the chamber of the lamp house, the upper wall of which is 90 provided with an air-escape port 28 between which and the discharge end of the air-pipe the socket members are located. Externally of the lamp house the air pipe is provided with a fan 29 which draws exterior air 95 into the pipe and forces it into the metal socket members, the cooling current thus set up entraining air within the chamber and forcing it through the escape port. The parabolic reflector casing and both reflectors 100 are out of contact with the lamp house walls. The parabolic reflector and the interior wall of the zone-shaped reflector are each out of contact with the lamp bulb, and the front brim of the zone-shaped reflector is formed 105 with an edge recess 30 whereby the zone-shaped reflector at its larger front end can be positioned relatively to the filament or point of light, with the edge wall of the recess 30 preferably out of contact with the 110 socket member of the lamp. Thus air spaces are obtained between the reflectors, the lamp, and the lamp house walls, and the rising hot air within the lamp house chamber and around the reflectors and the lamp is 115 entrained by the forced air current at the top of the chamber, and forced out through the port 28. Overheating of the lamp house chamber results in undue shortness of life 120 of electric lamps therein and also tends to 125 130

impair the silvering of the reflector backs or exterior surfaces when the reflectors are of silvered glass.

What I have above termed an annular spherical zone-shaped reflector is a most important feature of my invention, but while form or shape is of the essence of its utility, I do not wish to be understood from the following particularity of description as intending to limit my invention in any degree beyond what the state of the prior art may legally require; and I point out that the interior configuration of the spherical zone-shaped reflector is of comparatively slight importance as compared with the exterior configuration, for it is the outside surface of a reflector adjacent the silver that determines the direction of the reflection of the light rays.

For the best results in some uses, when the annular spherical zone-shaped reflector and the parabolic reflector are separate reflectors as above described, the annular zone-shaped reflector is primarily an exteriorly spherical zone measuring (Fig. 4) about 43° from *a* at its smallest diameter to *b* at its largest diameter; the open smaller rear opening of the reflector being subtended by an arc of 64° as indicated by the concave or parabolic mirror. The larger front end of the reflector forward of the diameter at *b* has an outwardly flaring integral conoidal brim 31 the outer face of which is at an angle of $25\frac{1}{2}^\circ$ to a line tangent to the point *b*, and the width of this angular or conoidal brim from *b* to *c* is such that the annular zone-shaped reflector as a whole is an approximate hemisphere in the sense that the front edge of the reflector as a whole is at the diameter of a sphere.

Both surfaces of the conoidal brim 31 and of the spherical zone-shaped portion of the reflector are preferably formed with a plurality of rows of flat-faced reflecting surfaces or facets 32, each row extending from the smaller end of the reflector to the outward edge of the conoidal brim. The exterior facets in each annular series are at an angle one to the other, and the exterior facets of the same series are also at an angle one to the other, and the facets in each exterior and each interior annular series are severally at an angle to an adjacent facet in one or more other series. As shown there are fourteen rows of five complete facets each, and two rows of three complete facets each, four facets being practically lost by the cut-out forming the edge recess 30.

This annular flaring reflector, if made of glass silvered on its exterior surface, is made of one piece of glass to prevent the refraction which would occur at the lines of angular departure of one facet from another if the facets were made of separate pieces abutted edgewise together. It is practically im-

portant to make such flaring reflector of one piece of glass, and I have found that the same can be practically manufactured at low cost with the exterior and interior series of angularly disposed and opposed facets. It is also practically important that the electric lamp should be contained within the chamber of the annular flaring or zonal reflector, and this means that such reflector must have a recess in its brim for reception of the lamp socket if the most effective conservation of light rays is to be effected in motion picture projection and photographic enlargement or other operations.

The lines *x* indicate reflected light rays that pass in parallelism through the condenser lens and then converge at a focal point at the center of the usual objective lens 33^a after passing through a film positioned at 34 as usual in motion picture projection.

If the reflecting surface of the reflector brim were either in the arc of the circle of the spherical portion of the reflector, or curved inwardly, numerous rays instead of being reflected into the condenser lens as shown, would not pass properly through the condenser lens. But the brim may be omitted although it is economically desirable to retain it for the conservation of all the rays that by seeming possibility can be conserved for passage in parallelism through the condenser lens.

Various changes can be made from what are set forth above as different forms of my invention, without departure from it.

Some important advantages of my new spherical zone reflector independently of its integral brim, and when combined with a parabolic mirror and incandescent lamp are: the apical junctions of the adjacent integral facets 32, which junctions are indicated by the lines 33 which severally extend from the smaller back opening of the spherical zone reflector to its larger front opening, are severally continuous in a straight line, each being at the apex of a series of interiorly acute and exteriorly obtuse, angularly-disposed adjacent integral facets; the series of facets between any two of the lines 33 being severally trapezoidal when viewed in plan, and successively increasing in length from the smaller end to the larger end of the reflector; that is, the location of the facets is not such as to bring the ends of any trapezoidal facet in an annular series thereof between the ends of a trapezoidal facet in an adjacent annular series and thereby create such a multiplicity of irregularly-disposed angularly-arranged facets as would cause the light rays reflected from the glowing images in some of the facets to interfere unduly with light rays emanating from glowing images in other facets. By my integral structure of the facets I avoid the use of all interiorly circu-

lar ribs of any material, such ribs if of metal interfering with the reflection, and if of glass causing light-ray aberration. The facets of my spherical zone reflector are not 5 panes of silvered glass set in a framework as heretofore. They have reflecting portions of equal intensity and it is the main object of this invention to produce a one-piece interiorly and exteriorly faceted glass reflector 10 wherein the facets are reflecting portions of equal intensity and have no edge portions exposed to the light rays, but surface portions only, the interior of the spherical zone reflector being free from all light-ray-aberration- 15 causing joints, walls and ribs so that it becomes in use as it were uniformly incandescent.

What I claim is:

1. As a new article of manufacture, an 20 annular reflector comprising a spherical zone and a therewith-integral outwardly-flaring conoidal brim, the exterior and interior surfaces being each formed with a plurality of annular series of facets which 25 are angularly disposed one to another; the facets in each annular series being severally angularly disposed to a facet in a contiguous series; and the spherical zone portion of the reflector measuring about 43° from its least 30 to its greatest diameter; and its smaller end opening subtending an arc of about 64°; the integral facets being of trapezoidal shape and the angularly disposed adjacent ends of the facets in each series merging in a continuous 35 apical line from the smaller end opening to the larger end opening of the spherical zone, and the facets being of equal reflecting intensity.

2. In the structure of claim 1, an imperforate parabolic reflector at the smaller end of the annular reflector; the brim of the latter having a lamp socket receiving space; an incandescent electric lamp; and combined with the reflectors, lamp and its socket, 45 means for adjusting the reflectors one in relation to the other; and means of adjusting the lamp relatively to the two reflectors.

3. A spherical zone reflector of one piece

of suitable material, the interior surface being formed with a plurality of annular series of trapezoidal facets which are angularly disposed one to the other in each series, each facet in each annular series being angularly disposed to a facet in a contiguous series, each inward facet being 55 opposed to a corresponding exterior facet, and said faceted surfaces being of like reflector construction, jointless, free from projections, and continuously smooth, and said facets merging directly and integrally one 60 into another at a projectionless angle, the facets in each annular series reflecting the filament when incandescent; in combination with a fixture for holding an incandescent lamp with its filament within the chamber of 65 the reflector; and such lamp; the said spherical reflector having an outwardly flaring integral reflector brim at its larger end, and the brim being formed with an incandescent lamp receiving opening; and a parabolic reflector at the smaller end of the reflector.

4. A spherical zone reflector of one piece of suitable material, the interior surfaces being formed with a plurality of annular serial of trapezoidal facets which are angularly disposed one to the other in each series, each facet in each annular series being angularly disposed to a facet in a contiguous series, each inward facet being opposed to a corresponding exterior facet, and said 75 faceted surfaces being of like reflector construction, jointless, free from projections, and continuously smooth, and said facets merging directly and integrally one into another at a projectionless angle, all the facets 80 in each annular series reflecting the filament when incandescent; in combination with a fixture for holding an incandescent lamp with its filament within the chamber of the reflector; said reflector having a rigid exterior support movably mounted in a guideway; said guideway; and such lamp.

In testimony whereof I have hereunto set my hand this 9th day of February, 1918.

WILLIAM VINCENT FOLEY.
